UNITED STATES PATENT OFFICE.

EDUARD RÜEGGER, OF ZURICH, SWITZERLAND, ASSIGNOR TO FIRM AKTIENGESELLSCHAFT DER MASCHINENFABRIKEN ESCHER WYSS & CIE., OF ZURICH, SWITZERLAND.

REFRIGERATING INSTALLATION.

Application filed May 14, 1923. Serial No. 638,892.

To all whom it may concern:

Be it known that I, EDUARD RÜEGGER, a citizen of the Republic of Switzerland, residing at Zurich, Switzerland, have invented 5 certain new and useful Improvements in Refrigerating Installations, of which the following is a specification, reference being had therein to the accompanying drawing.

The present invention has reference to a 10 contrivance for regulating the flow of cooling water through refrigerating machines, the condenser of which is cooled by streaming water.

With refrigerating machines of this type 15 damage to the condenser may occur especially in winter time owing to the freezing of the cooling water contained in the condenser. This danger exists in a high degree with automatic refrigerating machines, 20 which are automatically brought to a standstill, when a determined cooling temperature has been reached.

The object of the present invention is to 25 provide a contrivance by which the above drawback is overcome. To this end a contrivance for regulating the flow of the cooling water through the refrigerating machine, which contrivance is influenced in a known manner by the operation of the refrigerating machine, i. e. by the cooling action or by the working condition of the refrigerating machine, is provided according to the invention with two cut-off members one of which controls the inlet of the cooling water to the condenser and the other opens a passage permitting the cooling water contained in the refrigerating machine to flow off when the supply for the cooling water is closed and the refrigerating 35 machine is stopped.

A constructional example of the subject matter of the present invention is illustrated on the accompanying drawing which represents in an elevation a small automatic refrigerating machine, the regulating contrivance forming the subject matter of the present invention being shown in section.

In the drawing 1 denotes a cooling chamber into which the evaporator 2 of a small automatic refrigerating machine projects. 3 designates the condenser of this machine and 4 is the driving motor surrounded by a water cooled jacket, the motor serving to 50 drive the compressor which is surrounded

by the condenser 3 and is not indicated in the drawing. 5 is a switch for the electro motor 4 the switch being influenced by tilter 6. Switch arrangements of this type are known and are described in my copending application Ser. No. 478,412; as the switch 5 does not form the subject matter of the present invention a description of the switch is deemed to be superfluous. 7 denotes the cooling water supply pipe and 8 is the conduit through which the cooling water flows off. The flow of the cooling water into the condenser 3 is controlled by the regulating device A. The latter comprises a diaphragm casing 9 filled with an expansion medium, the casing being exteriorly influenced by the cooling action of the refrigerating machine. An over-saturated vapour with a certain quantity of liquid in excess is, for instance, filled into 75 the diaphragm casing 9, so that a comparatively small change in the temperature which is brought about by the refrigerating machine or by the surrounding atmosphere causes a comparatively large change of 80 pressure within the diaphragm casing 9, whereby the distance between the centres of the diaphragm walls is altered. As the wall of the casing which is on the left hand side when looking on the drawing is held 85 stationary by means of screw bolt 10, the opposite wall of the casing causes the movable rod 11 to move, for instance, towards the right when the cooling action decreases and the temperature increases. On the movable rod 11 two conical bodies 12, 13 acting as cut-off members are provided. The member 12 is adapted to co-operate with a seat 14 and the member 13 with a seat 15. The seats 14 and 15 are provided in a casing 95 16 which is rigidly fixed to a wall 17. The casing 16 comprises three chambers 18, 19 and 20 respectively. The supply pipe 7 is connected to the chamber 18. The chamber 19 is connected by means of a conduit 21 to 100 the point at which the cooling water enters into the condenser 3 and the chamber 20 is connected by the conduit 22 to the point in which the cooling water leaves the refrigerating machine.

During the working of the refrigerating machine, i. e. when the switch 5 is so influenced by the streaming cooling water as to keep the motor 4 operative, the various parts of the regulating device A occupy the 110

positions illustrated in the drawing. The cut-off member 13 permits the cooling water to pass from the chamber 18 to the chamber 19; the cut-off member 12, however, rests 5 against the seat 14, so that the cooling water flows through the condenser 3 and the cooling jacket of the motor 4 in the direction indicated by the arrows C. As soon as a determined low temperature is reached 10 within the chamber 1 the medium contained in the diaphragm casing 9 causes a displacement of the rod 11 towards the left, whereupon the open connection between the chambers 18 and 19 is interrupted and an open 15 connection between the chambers 19 and 20 is established. The water contained in the refrigerating machine flows thereupon by gravity and by the influence of the air entering the conduit 8 through the conduit 20 21 in the direction of the arrow B, indicated in dotted lines, and through the chambers 19 and 20 into the discharge conduit 8. In this manner the cooling jackets of the condenser 3 and of the motor 4 are emptied 25 whereby the danger of having these parts damaged by the freezing of the cooling water is removed.

I claim:

1. In a refrigerating plant, the combination with a cooling chamber, a refrigerating machine having a condenser cooled by flowing water and an evaporator in said cooling chamber; of means in said cooling chamber influenced by temperature changes, and two 30 cut-off members operated by said means, one of which controls the admission of cooling water to the condenser and the other of which controls a passage permitting the cooling water contained in the refrigerating machine to drain off when the admission of cooling water is prevented by the first mentioned cut off member.
2. In a refrigerating plant, the combination with a refrigerating machine having a condenser cooled by flowing water, a cooling chamber and an evaporator in said cooling chamber; of means in said cooling chamber influenced by temperature changes in said chamber, and two simultaneously and oppositely operated cut-off members actuated by said means, one of said members controlling the flow of cooling water to said condenser and the other controlling a passage permitting the cooling water contained in the refrigerating machine to drain off when the admission of cooling water is prevented by the first mentioned member.
3. In a refrigerating plant, the combination with a refrigerating machine having a condenser cooled by flowing water, a cooling chamber and an evaporator in said cooling chamber; of a single thermostatic means in

the cooling chamber influenced by temperature changes in the chamber, two cut-off members outside of said chamber, a rod connecting said means and members, one of said members controlling the flow of cooling water to said condenser and the other member controlling a passage permitting the cooling water contained in the refrigerating machine to drain off.

4. In a refrigerating plant, the combination with a refrigerating machine having a condenser cooled by flowing water, a cooling chamber, and an evaporator in said chamber; of a casing outside said chamber and having three compartments, one of said compartments having an inlet for cooling water and a port connecting it with the second compartment and the inlet to the condenser, a connection between the discharge of the condenser and the third compartment, said third compartment having a port connecting it with said second compartment and also having a liquid outlet, a thermostat in the cooling chamber and controlling means for the ports between the compartments arranged for operation by said thermostat.

5. In a refrigerating plant, a cooling chamber, an electrically operated refrigerating machine having a condenser cooled by flowing water and an evaporator in the cooling chamber; in combination with an electric switch controlling the operation of said machine, a tilter to operate the switch, means to control the supply of cooling water to said condenser, means to permit the water contained in the refrigerating machine to drain off when the supply of cooling water is cut off by the first means, a thermostatic device in said cooling chamber connected to both of said means, said tilter arranged to receive the cooling water discharged from the condenser as well as the cooling water drained therefrom.

6. In a refrigerating plant, a cooling chamber, a thermostat therein, an electrically operated refrigerating machine having a condenser cooled by flowing water and an evaporator; in combination with an electric switch for said machine, a tilter to operate the switch, a casing outside said chamber having three compartments, two simultaneously and oppositely actuated members each controlling communication between two of said compartments and operated by the thermostat, one of said compartments being connected to a water supply, the second connected to the inlet for cooling water for the condenser, and the third connected to the discharge of the condenser and discharging to said tilter.

In testimony whereof I affix my signature.

EDUARD RÜEGGER.
